CATHERINE HOLLAND, OF NEW YORK, N. Y., ASSIGNOR OF ONE-HALF TO FREDRICK R. HOLLAND, OF NEW YORK, N. Y.

DISPLAY-RACK.

1,047,053.

Specification of Letters Patent. Patented Dec. 10, 1912.

Application filed September 11, 1912. Serial No. 719,744.

To all whom it may concern:

Be it known that I, CATHERINE HOLLAND, a citizen of the United States, and a resident of the city of New York, Maspeth, borough 5 of Queens, in the county of Queens and State of New York, have invented a new and Improved Display-Rack, of which the following is a full, clear, and exact description.

10 This invention relates to display racks, and has particular reference to devices of this nature adapted especially for domestic use or in connection with private laundries, the primary object of the invention being 15 to provide a rack which embodies the following characteristics: cheapness of construction, facility to knock down and set up, lightness for transportation purposes, and stability of position while being used.

20 The foregoing and other objects of the invention are attained in the preferred embodiment by means of the devices herein-after fully described and claimed, and illustrated in the accompanying drawings forming 25 a part of this specification, in which like characters of reference indicate corresponding parts in all the views, and in which—

Figure 1 is a perspective view of the device in operative position; Fig. 2 is a vertical and partly sectional view on the line 30 2—2 of Fig. 1; Fig. 3 is a side elevation of the brace; Fig. 4 is a fragmentary plan view of the hanger; Fig. 5 is a detail view of one end of the hanger bar in combination with the adjacent upright; and Fig. 6 is a detail of the clamp described below.

Referring particularly to the drawings, I provide a pair of upright members 10, each of which has a pair of angularly arranged legs 11 the lower ends of which are 40 adapted to stand upon the floor and may, if desired, be connected by a cross piece 12, making a rigid construction with respect to the lateral bracing of the upright. The 45 upper end of each of said uprights is formed with a socket 10' extending longitudinally of the rack, the vertical opposing walls of the socket being flared outwardly toward the outside of the upright, as shown in 50 Fig. 5.

As a preferred means for securing the lower portions of the uprights in substantially rigid spaced relation to each other I

provide a brace 13 of peculiar construction, the same comprising a pair of strips 13' 55 connected together intermediate of their ends by means of a fastener 14, and the adjacent ends of which are spaced or flared apart and are maintained by means of spacing blocks 15. The strips 13' and the spacing 60 blocks 15, together with the several fastening means holding them in the position indicated, constitute a very light and rigid brace, the ends of which are parallel and vertical and adapted to lie snugly against 65 the opposing inner vertical walls of the uprights 10; said spacing blocks preferably are of substantially the same width as said uprights. Coöperating with each of the spacing blocks 15 and pivotally connected 70 thereto by means of a link 16 is a clamp block 17, which lies against the outer side of the upright from the spacing block 15. The effective length of the link 16 is slightly greater than the thickness of the upright 75 10 which lies within the same and between the two blocks 15 and 17. The lower limit of movement of the brace 13 will be determined by the contact of the links 16 upon the upper ends of the legs 11. Since 80 the brace is substantially a rigid structure the blocks 15 will be maintained at practically the same relation to each other. The links 16, therefore, will hold the clamp blocks 17 snugly against the uprights 10, 85 with the result that the uprights and brace will be held in a substantially rigid condition, and yet these parts are easily separated, when desired, for knocking down the rack by lifting the clamp blocks 17 and 90 the brace as a whole from the uprights.

The hanger 18 comprises a rail 19 having dovetailed ends 19' adapted to substantially fit into the aforesaid sockets 10' of the uprights, and to said rail 19 is connected 95 in any suitable manner, as by eyelets 20, a series of bars 21. The length of the rail 19, and the rack as a whole, may be as great as desired for any particular purpose, and hence the number of bars 21 may likewise 100 be increased as much as is necessary for such purpose. The connection 20 for each bar is preferably such that the entire series of bars may be collapsed, as indicated in Fig. 4, whereby the hanger will occupy a 105 minimum amount of space when the rack

is knocked down for storage purposes. The said connection 20, furthermore, insures a permanent symmetrical means of suspending the bar at its center, and also is sufficiently flexible to facilitate the hanging of a garment upon the bar or removing the same therefrom.

As one practical use for the bar it may be suggested that it will be stood at a convenient place where laundrying is being done, and as each skirt, waist, or the like, is laundried it will be hung upon one of the bars 21 instead of being hung across a line or the like, as is commonly done. The rack even when carrying a number of garments may readily be lifted up if necessary, and when not in use may be knocked down and stored away, occupying a comparatively small amount of space.

Having thus described my invention,

what I claim as new and desire to secure by Letters Patent is:—

The herein described display rack comprising a pair of uprights, each of said uprights having a pair of angularly arranged legs, a brace extending from one upright to the other and including a clamp block opposite each end adapted to embrace the adjacent uprights and a link securing said block in position and adapted to rest upon said legs, and a hanger extending between the tops of said uprights.

In testimony whereof I have signed my name to this specification in the presence of two subscribing witnesses.

CATHERINE HOLLAND.
